(57) **CLAIM**

The ornamental design for an electronic timepiece, as shown and described.

DESCRIPTION

FIG. 1 is a perspective view of the invention showing a watchband connected thereto in phantom;

FIG. 2 is a top plan view thereof;

FIG. 3 is a bottom perspective view thereof;

FIG. 4 is an end elevation view of FIG. 1;

FIG. 5 is an end elevation view of the other end of FIG. 1;

FIG. 6 is a left side elevation view of FIG. 1; and,

FIG. 7 is a right side elevation view of FIG. 1.

The broken lines shown in FIGS. 1 and 2 are for illustrative purposes only and form no part of the claimed design.

1 Claim, 4 Drawing Sheets

FIG. 1

FIG. 2

FIG. 3

FIG. 4

FIG. 5
